UNITED STATES PATENT OFFICE

160,722

CARD CONTROLLED ACCOUNTING MACHINE

George H. Kress, Vestal, N. Y., and Carl W. Sundberg, Detroit, Mich., assignors to International Business Machines Corporation, New York, N. Y., a corporation of New York

Application November 29, 1949, Serial No. 6,314

Term of patent 14 years

(Cl. D64—11)

To all whom it may concern:

Be it known that we, George H. Kress and Carl W. Sundberg, citizens of the United States of America, residing respectively at Vestal, county of Broome, State of New York, and Detroit, county of Wayne, State of Michigan, have invented a new, original, and ornamental Design for a Card Controlled Accounting Machine, of which the following is a specification, reference being had to the accompanying drawings, forming part thereof.

Fig. 1 is a perspective view of a card controlled accounting machine, embodying our design.

Fig. 2 is a side elevation of the same as seen from the left end.

Fig. 3 is a rear elevation of the same.

We claim:

The ornamental design for a card controlled accounting machine, as shown.

GEORGE H. KRESS.
CARL W. SUNDBERG.
